Tuson & Tuson

UNITED STATES PATENT OFFICE.

JAMES F. BURNS, OF PHILADELPHIA, PENNSYLVANIA, ASSIGNOR TO V. V. FITTINGS COMPANY, OF PHILADELPHIA, PENNSYLVANIA, A CORPORATION OF PENNSYLVANIA.

SAFETY DEVICE FOR ELECTRIC SWITCHES.

1,357,762.

Specification of Letters Patent.

Patented Nov. 2, 1920.

Application filed August 2, 1917. Serial No. 184,145.

To all whom it may concern:

Be it known that I, JAMES F. BURNS, a citizen of the United States, residing in Philadelphia, Pennsylvania, have invented 5 Safety Devices for Electric Switches, of which the following is a specification.

One object of my invention is to provide an electric switch and inclosing casing or box therefor, with a relatively simple and 10 substantial attachment whereby the lid or cover of said box is maintained in a locked condition preventing access to the switch until the latter has been moved to a fully opened position.

15 A further object of the invention is to provide an attachment of the character above indicated which shall include means for preventing the switch being moved to its closed position until the lid or cover of the 20 box has been closed;—the invention in its preferred form also contemplating means whereby said switch may be locked in its open position with the lid or cover closed.

These objects and other advantageous ends 25 I secure as hereinafter set forth, reference being had to the accompanying drawings, in which,

Figures 1 and 2 are respectively a front elevation and a bottom view of a switch box 30 and switch constructed according to my invention;

Fig. 3 is a side elevation of the structure shown in Figs. 1 and 2;

Fig. 4 is a bottom view, showing the cover 35 in a partly raised position;

Fig. 5 is a plan of the switch box and switch with the cover removed;

Fig. 6 is a vertical section on the line 6—6, Fig. 1;

Fig. 7 is a perspective view illustrating 40 one of the switch operating rods and its associated locking mechanism;

Fig. 8 is a transverse section on the line 8—8, Fig. 6;

Fig. 9 is a vertical section on the line 9—9, Fig. 8 showing one of the switch operating rods in its outer position;

Figs. 10 and 11 are two sections similar to those of Figs. 8 and 9 respectively, showing the various parts in the positions occupied when the lid of the switch box is opened; and

Fig. 12 is a vertical section similar to Fig.

9, but showing the switch operating rod or handle locked in its open position. 55

In the above drawings, 1 represents a switch containing box usually made of metal and having hinged to its upper edge a cover 2. Mounted within this box is a block or plate 3 of insulating material such as slate, 60 marble, etc., on which in the present instance are mounted three terminals, 4, 5 and 6, including binding screws or posts for the attachment of conductors and also having clips to which are pivoted the blades 7, 8 65 and 9, which with a connecting cross bar 10 of insulating material, constitute the movable part of the switch.

Also mounted on the base 3 are three terminals 11, 12 and 13, including clips for 70 the reception of the blades 7, 8 and 9, and also including other clips or holders for the reception of cartridge fuses. A second set of terminals 14, 15 and 16 is provided on the switch plate 3, and each of these includes 75 a clip for the reception of the second end of a cartridge fuse whose opposite end engages one of the clips 11, 12 or 13 as the case may be. Each of these terminals also includes a binding screw for the attachment of 80 a conductor and it is to be understood that suitable openings are provided in the front and rear ends of the box 1 to permit of the entrance thereto of the six conductors designed for connection to the terminals 4, 5, 85 6 and 14, 15, 16.

For shifting the position of the movable switch member 7—10, from its open to its closed position or vice versa, there is connected to the cross bar 10 a pair of rods 17 90 and 18 which pass through tubular guides 19 and 20 respectively at the front end of the box 1 and are connected at their outer ends by a transversely extending handle 21 of insulating material. Obviously without departing from my invention, one of the above noted operating rods may be dispensed with, but where the movable switch member is of a considerable transverse width, I preferably employ more than one rod as illustrated. 95

In any case, the means for operating the movable switch element includes a rod, in the present instance indicated at 17, having for the outer half of its length a relatively 105 large diameter portion 22, and for the bal-

ance or inner part of its length, a smaller diameter portion 23. In addition I provide on the small diameter part adjacent the inner end of the large diameter part 22 a collar 24. Obviously said rod is made in large and small diameter portions as a matter of convenience, since its essential feature resides in the provision of a shouldered recess, preferably of annular form, with a collar or equivalent projection adjacent thereto.

While as shown in Fig. 5, the second rod 18 is formed in two parts of different diameters, this is immaterial for purposes of my invention.

As illustrated in Fig. 4, the cover 2 of the switch box has a bottom portion 25, with slots or recesses 26 and 27 formed in its edge designed to permit of the passage of the latter below the switch operating rods 17 and 18, and it is noted that the first of these slots has a relatively narrow entrance whose width is sufficient to permit of the passage of the part 23 of the rod 17, but too narrow to pass the part 22. The latter however is of a diameter sufficiently small to permit of its sliding longitudinally through the larger part of this slot.

Mounted within the front end of the box, immediately adjacent the rod guide 19, is a bracket or supporting structure 28, illustrated as in the form of a casing held to the front of said box by a pair of bolts 29 and 30. This casing is in the form of an inclosing structure projecting above the top of the front of the box and having through its projecting portion a relatively large opening 31 for the passage of the rod 17 and its collar 24.

Within the casing provided by said structure 28 is a locking plate 32 pivotally mounted on the bolt 30 and at all times so acted on by a spring 33 as to tend to swing upwardly toward the switch operating rod 23. The outer end of said plate has a flattened or laterally extended head 34, immediately above which there is provided an opening 35 through the casing 28 for the passage of a pin or bolt 36 rigidly mounted in the front part of the cover 2;—the arrangement being such that the act of moving said cover to its closed position causes said pin to enter the opening 35 and by engaging the head 34, swing the plate 32 downwardly against the action of the spring 33, thereby withdrawing a projecting portion 37 of said plate from the vicinity of the switch operating rod 23.

As shown in Figs. 2 and 4, the cover has on one of its side edges a projecting perforated lug 38 designed to have its perforation in line with that of a second lug 39 projecting from the box 1 when said cover is closed, so as to permit of the hasp of a padlock 40 being passed through said perforations in order that the cover may be locked in its closed position.

With the above described arrangement of

parts, it will be understood that whenever the cover is in its open position and the movable switch member is likewise open, the latter is locked in such open position, since as shown in Figs. 10 and 11, the projection 37 of the locking plate 32 is maintained by the spring 33 in engagement with the small diameter portion 23 of the switch rod 17 to the rear of the collar 24 and obviously any inward movement of the switch handle is impossible after said collar strikes the projection 37.

Since the supply mains for the switch are connected to the terminals 4, 5 and 6, fuses may be now safely placed between or removed from engagement with the two sets of terminals 11, 12 and 13 and 14, 15 and 16;—the operator being additionally protected by the provision of a plate 41 of insulating material fastened to the cross bar 10 of the movable switch member and of such dimensions as to completely cover the three switch blades 7, 8 and 9, except where it is cut away to permit of engagement of said blades by the clips 11, 12 and 13.

When the cover 2 is moved to its closed position, in which it is normally held by a spring catch 42 engaging a projection such as a screw head 43 on the box, the pin 36, by engaging the head 34 of the locking plate 32, forces the latter with its projection away from the switch rod 17 so that it is possible by pressing in upon the cross bar 21, to move the switch blades 7, 8 and 9, into electrical engagement with the terminals 11, 12 and 13 and thus to close the switch.

When the parts are in these positions however, it is not possible to open or raise the cover, since as will be obvious from Figs. 4, 5 and 6, the large diameter portion 22 of the operating rod 17 has been entered in the larger portion of the slot 26 in the cover and cannot be moved upwardly with the latter because of its passage through the guide 19. There is no possibility therefore of removing the fuses or of otherwise tampering with the switch until the blades thereof have been moved to their fully opened position and the larger portion of the operating rod 17 has been replaced in the slot 26 of the cover by the smaller diameter part thereof,—when the cover may be raised.

If it be desired to lock the switch blade in its open position when the box cover is closed, this is done by first drawing the handle 21 outwardly as far as possible to open the switch, then opening the cover and finally by drawing the handle with the switch blade still farther out, thus causing the collar 24 on the rod 17 to move from a position immediately adjacent the locking plate 32 (Figs. 10 and 11), to the position shown in Fig. 12 within the guide 19. Thereafter when the cover is again closed

and if desired, locked by a padlock 40, it is not possible to close the switch, since the collar 24 on the rod 17 is of appreciably larger diameter than the part 22 and the slot 26 and therefore comes into engagement with the outer face of the cover 2 and prevents such closure.

When it is desired to again close the switch, it is necessary to first raise the cover, move the handle inwardly until the collar 24 strikes the locking plate 32, (Fig. 11) and then again move the cover to its closed position in which said locking plate is depressed by the pin 36. The switch handle is then free to be moved inwardly to close the switch, it being noted that Fig. 7 shows the parts in the positions occupied when the switch blade is locked in its outer position, while Fig. 9 shows the same parts after the switch handle has been moved sufficiently far toward its closed position to permit the collar 24 to clear the locking plate.

From the above description it will be seen that by the use of the relatively simple and substantial mechanism illustrated, it is not possible to open the switch-containing box until the switch has been fully opened nor is it possible to ordinarily close said switch until the cover has been closed. Further, the movable switch member may be conveniently locked in its open position and retained therein by locking the cover shut.

35 I claim;—

1. The combination of a box having a cover movably mounted thereon; an electric switch in said box; a rod for operating said switch mounted to be longitudinally movable through an open sided opening in the cover and having an enlargement maintaining the cover closed until the switch is open, said rod being formed to pass out of the open side of the opening in the cover 45 when in a position in which the switch is open.

2. The combination of a body having a cover provided with an opening having a relatively narrow entrance; an electric switch in said box; and an operating member connected to the switch and movable longitudinally through the opening of the cover, said member having a portion incapable of passage through the entrance of said opening and positioned to lie within the opening so as to prevent opening of the cover except when the switch is open.

3. The combination of a box having a cover provided with a recess in one edge having a main portion and a narrow side entrance thereto; an electric switch in said box; and an actuating member for the switch operative in said recess of the cover and having a portion locking the latter closed when the switch is closed and in-

cluding a relatively narrow portion positioned to pass through the narrow side entrance of the recess in the cover to permit opening of the latter only when the switch is open.

70

4. The combination of a box having a cover provided with a recess in one edge having connected wide and narrow portions; an electric switch in said box; an operating member for the switch having a part operative in the side portion of the recess of the cover and formed to lock said cover closed when the switch is closed and also including a relatively narrower portion positioned to pass laterally through the narrow part of the recess to allow opening of the cover only when the switch is in its open position.

80

5. The combination of a box having a cover provided with an opening in one edge formed with a relatively narrow entrance; an electric switch in the box; and an operating member for the switch consisting of a rod engaged by the box so as to be held from movement with the cover open and including a narrow portion capable of passing through the entrance of the opening in the cover and also having a wider portion incapable of passing said entrance but slideable within the body of the opening, the narrow part of said member being placed to lie adjacent the entrance to the opening of the cover only when the switch is open.

85

6. The combination of a box having a cover hinged thereto and provided in one edge with an opening having a relatively narrow entrance; a switch in the box; and at least one operating rod for said switch held from bodily lateral movement but longitudinally guided in the box and having a portion slideable in the opening thereof but incapable of passing the entrance to said opening, said rod also having a part of a width capable of passing through the entrance to the opening in the cover and so placed as to lie adjacent said opening only when the rod is in a position corresponding to the open position of the switch.

90

7. The combination of a box having a cover; a switch in said box having an operating rod including a collar and two portions of different widths, the cover having a recess with a narrow entrance capable of receiving the narrow part of the rod but incapable of passing the wider portion thereof; with a locking bolt on the box actuated by the cover and positioned to engage the collar to hold the switch operating rod from movement as long as the cover is open.

115

8. The combination of a box having a cover; a switch in said box; with a longitudinally movable switch operating member extending outside of said box, including means co-operating with the cover for pre-

125

130

venting longitudinal movement of said member and closure of the switch when said cover is closed.

9. The combination of a box having a cover; a switch in said box; with a longitudinally movable operating member for the switch having an abutment coöperating with the cover to prevent movement of said member and closure of the switch when the cover is closed.

10. The combination of a box having a cover; a switch in said box; an operating member for the switch having an abutment coöperating with the cover to prevent closure of the switch when the cover is closed; and a lock on the box also coöperating with

said abutment to prevent closure of the switch under predetermined conditions when the cover is opened.

11. The combination of a box having a cover; a switch in said box; an operating member for the switch having an abutment coöperating with the cover to prevent closure of the switch when the cover is closed; with a lock on the box also coöperating with 25 said abutment and operative by the cover for preventing closure of the switch under predetermined conditions when the cover is opened.

In witness whereof I affix my signature. 30

JAMES F. BURNS.
